Primary Examiner — Patricia A Palasik(74) *Attorney, Agent, or Firm* — Baker Botts L.L.P.; Michael A. Sartori(57) **CLAIM**

The ornamental design for a drill bit, as shown and described.

DESCRIPTION

FIG. 1 is a front view of a drill bit in accordance with an embodiment of the present design;
 FIG. 2 is a rear view thereof;
 FIG. 3 is a right side view thereof;
 FIG. 4 is a left side view thereof;
 FIG. 5 is a top view thereof;
 FIG. 6 is a bottom view thereof;
 FIG. 7 is a first perspective view thereof;
 FIG. 8 is a second perspective view thereof;
 FIG. 9 is an enlarged view of portion 9 of FIG. 1;
 FIG. 10 is an enlarged view of portion 10 of FIG. 2;
 FIG. 11 is an enlarged view of FIG. 4;
 FIG. 12 is an enlarged view of portion 12 of FIG. 5;
 FIG. 13 is an enlarged view of portion 13 of FIG. 6;
 FIG. 14 is an enlarged view of portion 14 of FIG. 7; and,
 FIG. 15 is an enlarged view of portion 15 of FIG. 8.
